UNITED STATES PATENT OFFICE

WINTHROP L. CARTER, OF NASHUA, NEW HAMPSHIRE, ASSIGNOR TO NASHUA SURE-HOLD COMPANY, OF NASHUA, NEW HAMPSHIRE, A CORPORATION OF MASSACHUSETTS

HOLDING BAND

Application filed January 21, 1929. Serial No. 333,915.

This invention relates to means for holding articles in proper shape, or groups of articles properly assembled, and refers particularly to paper bands adapted to surround articles 5 or groups of articles, an end portion of each band having a coating to enable it to be adhesively connected to another surface portion of the band after being wrapped around the article or group.

10 As is well known, practically all adhesive materials when applied to paper and then dried, cause the coated portion of the paper to curl, and such curling interferes with proper manipulation of the paper to apply it to 15 the use for which it is intended. Such curling particularly affects the coated ends of rather narrow and usually thin paper strips such as employed for the purposes for which the present invention is intended, such as holding 20 laundered articles. Therefore one of the objects of my invention is to provide holding bands which may be economically produced and having adhesive-coated end portions possessing a minimum tendency to curl.

25 Another object is to provide paper bands having adhesive-coated end portions which may be manipulated by a person without soiling one's fingers by contact with the adhesive.

Another object is to provide such bands 30 with extreme transverse end edges which are provided with no exposed adhesive and which, when the bands are to be removed from the articles wrapped therein, provide narrow free tabs that may be grasped and pulled to effect 35 removal.

With the above objects in view, the invention consists in the bands substantially as hereinafter described and claimed.

40 Of the accompanying drawings:

Figure 1 is a plan view of one of the improved bands but illustrating it with the folded end edge turned back to indicate the full area of adhesive employed.

45 Figure 2 is a plan view of the completed band.

Figure 3 represents a section on line 3—3 of Figure 2 on a much enlarged scale.

Similar reference characters designate sim- 50 ilar parts or features in all of the views.

As illustrated, a strip *a* of paper, which may be of any desired length and width, has a limited end area coated with adhesive *b*, the adhesive being applied while the paper is flat or substantially so, preferably in the manner presently described, the coating extending to the extreme end of the strip as illustrated by Figure 1. Then, and preferably before the adhesive dries, the paper is folded on a transverse line *c* close to the extreme end 55 edge of the paper, so as to present a narrow un-coated surface *d* as illustrated by Figure 2. Such folding brings two layers of the adhesive *b* face to face and effects retention of the strip end in folded condition. In Figure 3 the coating *b* is illustrated as spaced from the paper, but this is only to clarify the structure.

The preferred method of making the bands is to coat a marginal portion of a web of paper 70 with a suitable adhesive, then fold the extreme edge of said coated margin upon itself, and then, after drying the adhesive, transversely cut the web into strips.

I do not limit myself to folding the paper 75 on but one line *c*. It may be folded on two or more parallel transverse lines so that the tab end of the strip may consist of three or more thicknesses of paper instead of the two thicknesses illustrated by Figure 3.

It will now be understood that the bands are very economically produced, especially since each consists of a single strip of paper, having no separate piece attached thereto. And certain advantages of the structure are 85 as will now be explained.

The end transverse folding results in the end of the band consisting of a plurality of layers of paper which effect such stiffening as to largely counteract the tendency of a dry-gummed piece of paper to curl. Without such doubling, or tripling if desired, and without a separate tab member applied, the dry-gummed end of the strip would so curl as to interfere with packaging of the bands, or 90 the proper handling of them when applying them to use.

When a band is being applied to use, the person effecting such application simply 95 grips the folded end both surfaces of which 100

carry no adhesive as illustrated by Figure 3, and therefore does not need to touch any gummed surface either while moistening the gum or when wrapping the band around an article or package and affixing the gummed area to the other end of the band. Therefore the user's hands may avoid becoming soiled.

Then when an applied band is to be removed from the article or package, the free and un-attached folded end presents a tab which, by pulling it, enables the band to be quickly removed.

Owing to the fact that the strip of paper is imperforate in the sense that it has no perforations that would tend to unduly weaken it, it can be depended upon to reliably confine articles surrounded by it.

Having now described my invention, I claim:

A band for holding articles, comprising an elongated imperforated strip, a narrow end edge of which is folded to provide a plurality of layers, a limited area of the strip adjacent to said folded end having a dry-gum coating.

In testimony whereof I have affixed my signature.

WINTHROP L. CARTER.
